Primary Examiner — Katie Jane Stofko(74) *Attorney, Agent, or Firm* — Stinson LLP(57) **CLAIM**

The ornamental design for a pet chew, as shown and described.

DESCRIPTION

FIG. 1 is a perspective of a pet chew of the present design; FIG. 2 is a front elevation of the pet chew; FIG. 3 is a rear elevation of the pet chew; FIG. 4 is a top plan of the pet chew; and, FIG. 5 is a bottom plan of the pet chew.

The broken lines shown at opposite end portions of the pet chew in FIGS. 1–5 indicate that the appearances of the end portions form no part of the claimed design.
